UNITED STATES PATENT OFFICE.

EDGAR JAY, OF LONDON, ENGLAND.

BINDER FOR LOOSE-SHEET BOOKS.

938,057.

Specification of Letters Patent. Patented Oct. 26, 1909.

Application filed December 23, 1908. Serial No. 468,939.

To all whom it may concern:

Be it known that I, EDGAR JAY, merchant, a subject of the King of Great Britain and Ireland, and residing at 16 Albion Buildings, Aldersgate street, London, E. C., in the city of London, England, have invented certain new and useful Improvements in Binders for Loose-Sheet Books, of which the following is a specification.

10 This invention relates to improvements in the binding or clamping together of the sheets of loose sheet books such as note books, ledgers, photograph, stamp, or post-card albums, letter files or the like, and other books requiring the removal and interchanging of such sheets and has for its object to provide means for readily removing one or more of the sheets and replacing them, or others in substitution therefor, firmly and 20 securely in position between the covers of the book. For this purpose I fix to the inside of the board forming the cover to which the sheets are to be bound and at one side of the same, near the back or folding edge, a strip or bar of metal or other suitable material, formed at one end with a flange at right angles thereto, and to the outer end of this flange is hinged a second metal strip or bar whose other end is formed with a notch. 30 To the corresponding end of the first named strip or bar is pivoted a catch which when turned into its locked position engages with the said notch of the hinged bar and is formed with a horizontal flange which bears 35 upon the latter for causing it to clamp or grip the sheets between it and the bar fixed to the cover. The latter bar is also provided with two or more vertical pins which pass through holes made in the sheets to be bound 40 and also through holes in the hinged or clamping bar when the same is locked. The sheets are thus securely held or bound together by the said pins and the clamping bar holding them in position thereon; and in 45 order to remove one or more of the sheets the pivoted catch is turned back, thus freeing the clamping bar and permitting of its being turned up out of engagement with the pins, thereby allowing the sheets to be drawn 50 off the latter.

Instead of a pivoted catch at one end I may employ a catch at each end pivoted to the bar or to the board or cover to which the sheets are bound, the clamping bar being in 55 this case separate and formed with a notch at each end for engaging with both the

catches when in their locked positions. And in order that my invention may be clearly understood reference is made to the accompanying sheet of drawings in which—

60

Figure 1 is an end view of a loose sheet book with the covers closed, Fig. 2 is a cross section of the same partly broken away, Fig. 3 is a longitudinal section of the binding device and cover with the leaves omitted, and Fig. 4, is a plan of the device. Fig. 5 is an 65 end view of the device showing the pivoted catch, and Fig. 6 shows one end of the device with the catch open and the clamping and fixed bars in section. Fig. 7 is a side 70 view of the device showing the pivoted catch open and the clamping bar raised for the purpose of removing or of inserting a sheet or sheets. Fig. 8 is a similar view showing a pivoted catch at each end, and Fig. 9 is a 75 plan of the top or removable clamping bar.

a are the covers of the book formed and bound together in the usual manner and *b* is the metal strip or bar fixed by rivets *b'* to the cover *a* near the back or folding edge 80 of the same.

c is the vertical flange formed at one end of the bar *b*, and *d* is a strip or bar similar to *b* hinged at *d'* to the flange *c* and formed at the other end with the notch *d''*. 85

e is the locking catch pivoted to the other end of the bar *b* and formed with the right-angled flange *e'*.

f, *f* are the vertical pins formed on or fixed to the bar *b*, and *d''* are the holes in the 90 bar *d* with which the pins *f* engage when the said bar is in its locked position as shown in Fig. 3.

The loose sheets *g* to be bound together are previously pierced with holes for filing 95 them on, or engaging them with, the pins *f*, and after the sheets have been thus filed the bar *d* is turned down upon them thus engaging the pins *f* with the holes *d''* in the bar. The catch *e* is then turned up so as to 100 cause its vertical arm to engage with the notch *d''* while its horizontal flange *e'* lies upon the top of the bar *d* thus securely locking the latter and clamping it down 105 upon the sheets *g*. By this means the said sheets are securely held in position on the pins *f*, and cannot be removed unless the bar *d* is unlocked and raised, as shown in Fig. 7, in which position the sheets are free for disengagement, and removal, from the said pins. Fresh sheets may also be inserted and 110 bound together by engaging the holes formed

therein with the pins *f* and clamping the bar *d* upon the same by turning the catch *e* into its vertical or locked position as shown in dotted lines in Fig. 6.

5 The pivoted catch *e* may be fitted at both ends of the device, as shown in Fig. 8, instead of at one end only. In this case the upper bar *d* is separate from, instead of being hinged to the device, and the said bar is 10 formed with a notch *d*² at each end for each of the pivoted catches *e* to engage with when turned into their locked positions, as shown, for clamping the bar upon the sheets *g*.

Having now fully described the nature of 15 my said invention, what I claim and desire to secure by Letters Patent is.

1. Improvements in loose sheet books consisting of a bar or strip of metal, or other suitable material, formed at one end with a 20 vertical flange to the top of which is hinged a second bar or strip, the first-named bar being attached to the cover of the book and being provided with two or more vertical pins which pass through holes formed in the 25 sheets to be bound as well as through holes in the hinged bar, the latter bar being held in its locked position by a catch pivoted to

the other end of the fixed bar and engaging with a notch in the end of the hinged bar, the loose sheets being thus securely held 30 by the pins between the said bars, substantially as herein described and shown.

2. In a device for bending and clamping together loose sheets, the combination of a bar, formed at one end with a vertical flange, 35 of a bar hinged at one end to said flange and formed at its other end with a notch, a locking strip pivoted to the other end of said bar and formed with a right angled flange, one of said bars being provided with pins 40 extending at right angles thereto and the other with holes to receive said pins when the bar is in locked position, combined with covers to one of which the first named bar is secured near the flaring edge, the said notch 45 at one end of the bar co-operating with the locking catch.

In witness whereof I have hereunto set my hand in the presence of two witnesses.

EDGAR JAY.
